[57] CLAIM

The ornamental design for a vegetable mill, as shown and described.

DESCRIPTION

FIG. 1 is a top and side perspective view of a vegetable mill showing my new design;

FIG. 2 is a side elevational view thereof, the side opposite that shown in FIG. 2 being the mirror image thereof;

FIG. 3 is an elevational view thereof rotated 90° from the FIG. 2 position;

FIG. 4 is an elevational view thereof from the side opposite that shown in FIG. 3;

FIG. 5 is a top plan view thereof; and,

FIG. 6 is a bottom plan view thereof.
